CHRISTMAS DECORATION SUPPORT

Howard D. Kors, 236 S. Ridge St.,
Crown Point, Ind. 46307

Filed May 31, 1973, Ser. No. 365,565

Term of patent 14 years

Int. Cl. D11—05

U.S. Cl. D29—1 A

FIG. 1 is a front elevational view of a Christmas decoration support showing my new design;

FIG. 2 is a left side elevational view;

FIG. 3 is a right side elevational view;

FIG. 4 is a bottom plan view; and

FIG. 5 is a rear elevational view.

I claim:

The ornamental design for a Christmas decoration support, substantially as shown.
